UNITED STATES PATENT OFFICE.

ANTHONY W. WERMERSKIRCHEN, OF CHICAGO, ILLINOIS.

DESIGN FOR A DISPLAY-STAND FOR EXHIBITING WOOD-FINISHES OF DOORS OR
SIMILAR ARTICLES.

42,844.

Specification for Design.

Patented July 30, 1912.

Application filed February 14, 1912. Serial No. 677,639. Term of patent 7 years.

To all whom it may concern:

Be it known that I, ANTHONY W. WERMERSKIRCHEN, a citizen of the United States, residing at Chicago, in the county of Cook and State of Illinois, have invented a new, original, and ornamental Design for a Display-Stand for Exhibiting Wood-Finishes of Doors or Similar Articles, of which the following is a specification, reference being had to the accompanying drawing, forming part thereof.

The figure is a perspective view of a sample exhibiting device, showing my new design.

I claim:

The ornamental design for a display stand for exhibiting wood finishes of doors or similar articles, as shown.

ANTHONY W. WERMERSKIRCHEN.

Witnesses:

MICHAEL J. STARK,
FRIEDA T. LEBERSTEIN.
